DESIGN FOR A JAR

Frederick W. Stewart, Beaver, Pa., assignor to
The Phoenix Glass Company, Monaca, Pa., a
corporation of West Virginia

Application August 31, 1934, Serial No. 53,133

Term of patent 3½ years

To all whom it may concern:

Be it known that I, FREDERICK W. STEWART, a citizen of the United States, residing at Beaver, in the county of Beaver, State of Pennsylvania, have invented a new, original, and ornamental Design for a Jar, of which the following is a specification, reference being had to the accompanying drawing, forming a part hereof.

Figure 1 is a perspective view of a jar showing my new design; Fig. 2 is a face view of the jar; Fig. 3 is a plan view thereof, and Fig. 4 is a sectional view showing the peripheral contour of the jar, on the line IV—IV of Fig. 2.

I claim:

The ornamental design for a jar, as shown.
FREDERICK W. STEWART.
